DISCHARGE TUBE OR THE LIKE

Walter Louis Krah, Swampscott, Mass., assignor
to Hygrade Sylvania Corporation, Salem, Mass.,
a corporation of Massachusetts

Application April 19, 1934, Serial No. 721,286

12 Claims. (Cl. 250—27.5)

This invention relates to electric discharge devices and with particularity to devices generally referred to as radio tubes, vacuum tubes, or the like.

5 An object of the invention is to provide novel means for supporting the electrode assembly of an electron discharge tube or the like.

Another object is to provide a novel device for resiliently supporting an electrode assembly 10 interiorly against the wall of an enclosing envelope or the like.

In radio tubes generally, and more especially in the modern types of tubes, it is imperative that the various electrodes of the electrode assembly 15 be maintained accurately in predetermined spatial relations, both with respect to one another and also with respect to the wall of the enclosing envelope. The necessity for maintaining the electrodes in fixed relation to the envelope is occasioned by the undesirable effects of changes 20 in capacitance between the electrodes of the tubes and surrounding shields or other conductors. Furthermore, it is often impracticable to secure the elements of tubes in fixed relation to one another by interposing an insulating spacer between 25 them and it is more convenient to minimize relative motion between the electrodes by supporting, those elements which are most inclined to move, against the inner walls of the envelopes. Supporting the end of the structure further from 30 the press by bracing it against the envelope, minimizes the tendency for the supporting wires to be bent or the glass adjacent these wires to be cracked when the tube is submitted to severe 35 shock. If the means for supporting the electrodes against the envelope are non-resilient, the normal variations in the dimensions of the envelopes will result in small clearance between the supports and the larger envelopes and annoying rattles due to 40 intermittent collision between the supports and the envelopes will be occasioned by sound waves or other vibrations. The supports bearing 45 against the envelope should therefore be flexible, but must be sufficiently rigid to prevent motion of the electrodes when subjected to normal vibration which would otherwise result in microphonic disturbances in the output of the tube when the latter is in use.

Accordingly, one of the principal objects of 50 this invention is to provide a radio tube, lamp or similar device, wherein the filament or electrode assembly is supported both from the press as well as from the upper end of the envelope, whereby 55 variations in the characteristics of the tube are substantially prevented even when the tube is subjected to heavy jars or vibrations.

Another object of the invention is to provide a 60 so-called single-press tube with means for supporting the electrode assembly against tilting movement with respect to the press, without at

the same time materially increasing the assembly cost or assembly time.

A feature of the invention relates to a radio tube of the so-called "dome" envelope type in conjunction with a novel form of resilient spacer. 5

There is disclosed in Patent No. 2,111,002, a resilient spacer consisting of a specially shaped strip of mica or other resiliently deformable material, which is self-locked to the electrode assembly. As disclosed in said application, the mica 10 spacer member is adapted to engage the inner wall of a radio tube in such a way that the strip tends to conform itself to the curvature of said wall. Thus in the case of tubes having cylindrical domes, the spacer strip or strips tend to 15 assume the shape of a cylindrical sector, with the vertical edge portions of the strip substantially parallel the axis of the tube. In certain instances, the use of spacers such as disclosed in 20 said application, renders comparatively difficult the assembling of the electrode unit in the bulb, since the vertical lateral edge portions of the spacer strips must conform to the curvature of 25 the tube wall, and the relative movement between the envelope and electrode unit must be parallel to the vertical axis of the tube.

Accordingly, another feature of the present invention relates to a resilient spacer which provides the necessary resilient support to the electrode unit, and one which more readily adapts 30 itself to tube envelopes of different shapes and sizes. In carrying out this feature of the invention, there is preferably employed a strip of resiliently deformable material such as mica or the like, which is interlocked with the electrode assembly in such a manner that it is capable of 35 tilting movement with respect to the vertical axis of the tube, so that the strip does not have to conform itself to the curved contour of the tube wall.

40 Other features and advantages not specifically enumerated will be apparent after a consideration of the following detailed description and the appended claims.

While the invention will be disclosed herein as 45 embodied in specific forms, it will be understood that the invention is not limited thereto, but is capable of embodiment in tubes, lamps, and similar devices of different shapes and sizes.

Accordingly in the drawing, Figure 1 is an ele- 50 vational view, partly in section, of a typical form of radio tube embodying features of the invention. Figure 2 is a top plan view of Figure 1, with the resilient spacers removed. Figure 3 is a top plan view of Figure 1, showing the resilient 55 spacers in position. Figure 4 is a detailed side view of Figure 1 with one of the resilient spacers removed. Figure 5 is an enlarged detailed view of one of the resilient spacers according to the invention. Figure 6 shows a modified manner of 60

mounting the spacers. Figure 7 shows a modification wherein the spacers are in the form of wire strips.

Referring more particularly to Figure 1, the numeral 1 indicates generally any well-known type of bulb or envelope, such as employed in radio tubes, lamps or similar devices. As shown in the drawing, the envelope or bulb is provided with a reentrant portion 3, terminating in the usual press 4 into which are sealed the various lead-in and support wires. The bulb preferably, although not necessarily, terminates at its upper end in a substantially cylindrical dome portion 5. The electrode assembly is indicated generally in Figure 1 by the numeral 6, and this assembly may take any well known form. Merely for purposes of illustration, there is shown in Figure 4 a detailed electrode assembly such as is employed in so-called full-wave rectifier devices. As shown in Figure 4, the electrode assembly comprises a pair of anodes 7 and 8. Each anode, for example anode 7, may consist of a pair of metal plates 9, 10, each plate having a semi-circular depression extending longitudinally thereof to define a hollow cylindrical discharge space when the plates 9 and 10 are assembled as shown. Sealed into the press 4 are a pair of metal rods or wires 11 and 12. The anode 7 is fastened, for example by spot welding, to the rod 11, and in like manner the anode 8 is fastened to the rod 12. The plates 9 and 10 of anode 7 are also spot welded to a rod 13, and a similar rod 14 is spot welded to the plates of anode 8. Sealed into the press 4 are two sets of wires, 15, 16, 17 and 18, 19, 20. Supported by the wire 17 is a metal tube or sleeve 21 which has its exterior surface provided with a coating or coatings of electron emissive material such as ordinarily employed in so-called indirectly heated cathodes. Insulatingly supported within the sleeve 21 is a heater wire or filament 22, which has its ends connected respectively to the wires 15 and 16. Similarly, the wire 20, supports a cathode sleeve 23, which is provided with a filament or heater 24, the ends of which are connected to wires 18 and 19. The double electrode assembly above described is interlocked as a suit by means of an upper insulator disc 25 and a lower insulator disc 26. As shown in detail in Figures 2 and 3, the disc 25 is provided with perforations 27, 28, 29, 30 to receive the upper ends of the wire 11, 13, 14 and 12 respectively. The disc 25 is also provided with a pair of perforations 31, 32, to receive the upper ends of the cathode sleeves 21 and 23. It will be understood, of course, that the lower disc 26 is provided with perforations similar to those provided in disc 25. For the purpose of rigidly interlocking the discs 25 and 26 to the electrode assembly, each disc is provided with two pairs of openings 33, 34, 35, 36. Each disc is also provided with a pair of substantially T-shaped metal straps 37, 38, these straps being in turn welded or otherwise fastened to the anodes 7 and 8 as shown more clearly in Figure 4 of the drawing. By means of the discs 25, 26 and the metal straps 37, 38, 39, 40, all the component parts of the electrode assembly are interlocked as a unit and relative movement between the electrodes is eliminated.

Preferably the above described electrode assembly or unit is supported from the press 4 at such a distance that the upper disc 25 is within the dome portion 5 of the tube envelope. In order to prevent excessive vibration of the electrode assembly with relation to the press 4, there

are provided, as shown in Figures 1, 3 and 4, a pair of resilient spacer members indicated generally by the numerals 39, 40. Each of the spacer members is in general E-shaped, comprising a pair of parallel side portions 41, 42 and a central portion 43, joined by a yoke portion 44. The yoke 44 is undercut at 45, 46 to allow the side portions 41 and 42 to be flexed with respect to the portion 43. Portion 43 is provided with locking shoulders 47, 48, and likewise portions 41 and 42 are provided with locking shoulders 49 and 50. For the purpose of locking each spacer member in position, the disc 25 (Fig. 2) is provided with a pair of slots 51, 52, and the edge of said disc 25 is also provided with notches 53, 54 and 55, 56. The slot 51 for example, is adapted to receive the central portion 43 of a spacer member, while the notches 53 and 54 are adapted to receive the portions 41 and 42 of this same spacer member. It will be noted that the slot 51 is off-set with respect to notches 53 and 54, so that when the spacer member is assembled in position, the central portion 43 is substantially vertical while the lateral portions 41 and 42 are inclined, as shown more clearly in Figs. 1 and 3. It will be noted that slot 51 is provided with corners or shoulders 57, 58 to lock the spacer member against upward movement. Likewise the inner ends of notches 53 and 54 are adapted to engage the shoulders 49 and 50 to lock the spacer member against downward movement. As hereinabove stated, the spacer members are preferably of sheet mica or other similar flexible insulating material, so that when the portion 43 is inserted in slot 51, and portions 41 and 42 are inserted in notches 53 and 54, the springy character of the material forces the shoulders 47 and 48 into locking engagement with shoulders 57 and 58.

Preferably, the spacer members are so proportioned that the portions 41 and 42 project downwardly a sufficient distance below the disc 25, to engage the shoulder 59 of the bulb 1. This engagement may cause a very slight bending of the spacer portions 41 and 42 as shown in exaggerated form by the dotted lines (Fig. 1). It is to be noted, therefore, that because of the notches 53 and 54, the portions 41 and 42 of the spacer member, do not conform themselves in any way to the curved contour of the bulb 1, but merely flexibly engage the shouldered part of the bulb as indicated in Figure 1.

It is believed that the manner of assembling the spacer members 39 and 40 in the disc 25, will be obvious from the foregoing description. With the arrangement as described, the electrode assembly is supported at its upper end, by the four downwardly projecting portions 41 and 42 of the spacer members and any vibrations of the bulb are taken up by the flexible portions 41 and 42.

There are thus provided means for flexibly supporting the upper end of the electrode unit against the inner wall of the bulb. As is customary, the electrode unit is previously assembled together with the stem 3 and press 4 to form a "mount" which is inserted within the bulb 1 and suitably united thereto in any well known manner. Because of the particular design of the spacers as described, and their particular manner of mounting, the assembling of the mount within the bulb is relatively simple, and the spacers may be designed for use in tubes having domes of different internal diameters.

While the drawing shows the invention as embodied in a so-called "dome" type envelope, it

will be understood that it is capable of embodiment in any other known type of envelope. Furthermore, while the drawing shows two oppositely disposed spacers, a greater or less number 5 may be employed if desired. Similarly, while the drawing shows the spacers attached to the upper disc 25, similar spacers may, if desired, be attached to the lower disc 26.

Where it is not desired to employ an interlocking arrangement between the disc 25 and members 39, 40 the simplified arrangement as shown in Figs. 6 and 7 may be employed. In Fig. 6 only the disc 25 and the uprights 11 and 12 of the assembly of Fig. 4 are shown. The members 39 and 40 are replaced by mica strips or sheets 64 of the shape shown in Fig. 7. Each of these strips is formed with projections 62, 63 and a narrow neck portion around which is strapped a metallic strip 65, to general T-shape. 20 The projecting end 66 of each strap is fastened, for example by spot welding to the respective posts 11 and 12, preferably at such an angle that the strips 64 rest against the edge of disc 25 as shown. The strips or spacers 64 are so designed 25 that the projections 62, 63 alone engage the inner wall of the glass envelope 1, in a manner similar to that described in connection with members 39 and 40. Here again because of the inclined position of the members 64 only their lower ends 30 engage the wall 1 and consequently any flexing of these members is effected around an axis which is at an angle to the vertical axis of the electrode assembly.

Instead of employing mica spacers, metallic 35 wire spacers may be employed. Thus as shown in Figs. 8 and 9, the mica disc 70 which corresponds to disc 25 of Figs. 1 to 4, is provided at each end with a pair of aligned slits 71 and 72 through which is passed a flexible wire 73. The 40 median portion of each wire is offset as at 74, so as to lie against the upper face of the disc between the slits. The free ends 75, 76 of each wire are bent downwardly at an angle so as to engage the wall of the envelope 1 in the manner 45 shown in Fig. 9. Disc 70 may be fastened to the electrode unit in any suitable manner. For example the disc may be provided with metal eyelets 77 adapted to receive the upper ends of the plate support rods similar to rods 11 and 12 of Fig. 4, to which they may be welded or soldered. If desired, the tips of wires 73 where they engage 50 the envelope, may be coated with heat insulating material such as glass, mica or the like. If desired, the free-ended wires 73 may be attached 55 to one or more of the electrodes instead of being removable interlocked with the mica disc 70 as shown.

Various changes and modifications may be made herein without departing from the spirit 60 and scope of the invention. The subject matter disclosed herein and not claimed is claimed in copending application Serial No. 129,993, filed March 10, 1937 and Serial No. 190,203, filed February 12, 1938.

65 What I claim is:

1. In combination, an enclosing envelope, an electrode assembly mounted within said envelope, a pair of separable interlocked insulator members carried by said assembly, one of said 70 members having at least one downwardly extending free portion flexibly engaging the inner wall of said envelope.

2. In combination, an enclosing envelope, a

pair of interlocked members mounted within said envelope, one of said members having a yoke portion with spaced leg portions extending therefrom and interlocked to the other member so that only the said leg portions are in contact with the 5 envelope.

3. In combination, an enclosing envelope, having a shoulder, an electrode assembly mounted within said envelope, a strip of flexible material carried by said assembly and inclined to the 10 vertical axis of the envelope, and means supporting said strip in engagement with only the shoulder of said envelope.

4. The combination according to claim 3 in which said strip is provided with a yoke portion 15 with spaced leg portions extending therefrom and only the leg portions are in contact with said shoulder of the envelope.

5. Spacer means for a radio tube or the like comprising a disc, a strip of flexible insulating 20 material, said strip having a portion extending through said disc at substantially right angles thereto and interlocked therewith, and another portion inclined to said disc and interlocked therewith. 25

6. Spacer means for a radio tube or the like comprising a disc having a pair of aligned openings, and a third opening offset with respect to said pair of openings, and a strip of flexible material having a pair of projections interlocked 30 with the edges of said pair of openings and another projection interlocked with the edge of said third opening.

7. Spacer means for a radio tube or the like comprising an insulator support, a pair of flexible members separably interlocked with said support, each of said members having a pair of projections extending beyond said support and inclined at an angle thereto. 35

8. Spacer means for a radio tube or the like comprising a strip of mica having a pair of projections, an insulator support and means including shouldered portions on said strip and slots in said support for separably interlocking said strip and support, said strip when interlocked having 45 its projections inclined outwardly at an angle to said support.

9. Spacer means for a radio tube or the like comprising a support having a pair of aligned notches in the edge thereof, a slot in the body 50 thereof, a mica strip having a pair of projections positioned in said notches, and a central lug positioned in said slot.

10. Spacer means according to claim 9 in which said slot is offset with respect to said 55 notches, and said strip is provided with interlocking shoulders to prevent dislodgement thereof.

11. In combination, an enclosing envelope, an electrode unit extending along the vertical axis 60 of said envelope, and a pair of flexible strips carried by said unit, said strips being mounted so that adjacent ends converge toward the said vertical axis and the opposite ends extend outwardly beyond said unit into flexible engagement with the wall of the envelope. 65

12. In combination, an enclosing envelope, an electrode unit mounted within said envelope, and a pair of mica members mounted at opposite sides of said unit, said members being inclined 70 towards each other and having free ends engaging the envelope wall.

WALTER LOUIS KRAHL.
